UNITED STATES PATENT OFFICE

1,997,376

METHOD OF KNITTING AND WARP-THREAD FEEDING MEANS FOR USE IN KNITTING

Edwin Wildt and Henry Harold Holmes, Leicester, England, assignors to Wildt and Company Limited, Leicester, England, a British company

Application November 11, 1932, Serial No. 642,246
In Great Britain January 1, 1932

3 Claims. (Cl. 66—135)

This invention consists in improvements in or relating to knitted fabrics, to methods of knitting such fabrics and to warp-thread feeding means for use in knitting, and is concerned with the production of knitted goods having what is sometimes termed "non-laddering" properties. The invention is an improvement in or a modification of that described and claimed in prior United States application for Letters Patent No. 600,780, filed March 23, 1932, according to which ladder-proof knitted fabric comprises loops formed from ground- and warp-threads knitted together and where desired warp-thread loops are so disposed that they lie behind the ground-thread loops so that the latter appear on the face of the fabric.

According to the present invention, the method claimed in the aforesaid prior specification is modified in that the tension of a warp-thread, after the latter has been passed round its needle, is released prior to the loop-drawing operation of the needle taking that thread so as to permit the thread to bulge. The effect of this is that in bulging the warp-thread naturally tends to move towards the front of the needle-hook, whereas the tension in the ground-thread tends to hold the ground-thread to the back thereof thus positioning the threads in the needle-hook in the desired relationship for bringing the ground-thread to the face of the fabric after the combined loop of warp- and ground-threads has been knocked over.

The present invention also comprises an improvement in that type of warp-thread feeding means (referred to herein as "feeding means of the type described") having in combination means to move the feeder to wrap the thread round its needle and a thread-drawing device to draw off a length of thread sufficient for the wrapping operation without undue slack.

According to this feature of the invention, in warp-thread feeding means of the type described the thread draw-off device is shaped to release a warp-thread prior to the loop-drawing operation of the needle taking that thread.

In order that the invention may be more clearly understood a preferred example will now be described with the aid of the accompanying drawing, in which—

Figure 1 diagrammatically illustrates the feeding of the warp-threads to the needles in such a manner as to release the tension of the thread prior to the loop-drawing operation of the needle;

Figure 2 is an enlarged view of the hook portion of a specially shaped needle according to this invention, and

Fig. 3 illustrates diagrammatically the relative positions of the stitch-cam and the thread-release portion of the thread-drawing device.

Like reference numerals indicate like parts in the drawing.

In Figure 1 five warp-thread feeders are indicated at 14 each supplying a warp-thread 10 to a needle and the ground-thread is indicated at 11.

The needle on the extreme right is shown as just having received a wrapping of warp-thread 10 and in a position to take the ground-thread 11. The warp-thread is indicated as having had its tension just released and the effect is, as above stated, that the warp-thread tends to bulge while the ground-thread remains under tension with the result that the warp-thread naturally tends to go to the front of the needle-hook which is the desired relationship for bringing the ground-thread to the face of the fabric when the combined ground- and warp-thread loops have been knitted by the hook on the extreme left of Figure 1.

When a warp-thread drawing device is employed as described for example in prior British Patent No. 364,039 it is preferred so to design the draw-off member in that patent that it will release the warp-threads prior to the loop-drawing operation of the needle and thus permits the bulging to occur as described above. It is not intended to suggest that the draw-off member has a shape which will permit a sudden or rapid

release of the warp-thread, but whereas in the case of the prior patent above referred to the shaping of the release portion of the draw-off device was designed to keep the warp-thread relatively taut and thus closely around the needle, it will now be so shaped as to release or liberate the thread to a sufficient extent, prior to the loop-drawing operation, to enable the warp-thread to bulge slightly and sufficiently to ensure that it will come readily to the front of the ground-thread in the needle-hook. By this means the slack provided in the warp-thread will, as the needle descends, maintain the thread in its frontal position throughout the loop-drawing operation. The ground-thread will be fed under some tension however slight and this will aid in compelling the warp-thread to roll into the requisite position.

In addition to the release of the warp-thread its accurate plating in rear of the ground-thread is assisted by provision of a needle specially shaped as shown in Figure 2. In this form of needle the upper portion of the back is inclined forwardly as at 30 to present at the top of the hook a somewhat peaked curve as contrasted

with the usual type of rounded curve. As the needle descends to draw the combined loop of warp- and ground-threads the release of the warp-thread will enable it to spring to the top of the peaked hook whereas the tension of the ground-thread will draw that thread further down from the top. In Figure 2 the two threads of the old loop are shown near the top of the needle and just prior to the operation of knocking over.

It is to be understood that the bulge produced in the warp-thread at the time of its release is the direct result of the springy nature of the yarns such as artificial silk yarns, spun silk yarns and the like, and the shape of the bulge and its size will occur similarly at each operation provided that the warp-thread draw-off member is accurately shaped to give the required release at the proper time.

Figure 3 illustrates diagrammatically a thread draw-off member 34 by which a length of warp-thread sufficient for a wrapping operation is drawn off seriatim from the warp-thread supplies during or prior to the wrapping movement of the warp-thread feeder 14. The stitch-cam 15 is shown in relation to the thread draw-off device the direction of movement of which relatively to the warp-threads is shown by the arrow. It will be seen that the threads are released by the member 34 at the position 16 and this occurs immediately prior to the engagement of the appropriate needle 12 with the stitch-cam 15.

It will be understood that as described in the British Patent No. 346,039, the thread feeders 14 are flexible and are utilized to wrap the warp-threads round the needles by first passing each feeder through a gap between adjacent needles from one side to the other of a bank thereof, then deflecting it laterally and returning it in an opposite direction between a gap adjacent to that first

penetrated by the feeder at the commencement of the wrapping movement. As the mechanism for moving the feeders of itself forms no part of the present invention it is not illustrated.

We claim:

1. A method of knitting ground- and warp-threads which comprises wrapping a warp-thread round its needle, knitting the warp-thread to appear on the rear face of the fabric and, after the warp-thread has been passed round its needle and immediately prior to the loop-drawing operation of the needle, releasing the tension on said thread in order to permit the warp thread to bulge slightly, for the purpose described.

2. For a knitting machine, warp-thread feeding means comprising in combination a warp-thread feeder, means to move the feeder to wrap its thread round an associated needle, a thread-draw-off cam which is additional to the feeder and operates to engage the warp-threads seriatim and which is so shaped as to draw off sufficient yarn for the wrapping operation of each feeder and to release the tension in each warp-thread immediately prior to the loop-drawing operations of the associated needles.

3. For a knitting machine, warp-thread feeding means comprising in combination a warp-thread feeder, means to move the feeder to wrap its thread round an associated needle, a thread-draw-off cam which is additional to the feeder and which engages the warp-threads seriatim and which is shaped to draw off sufficient yarn for the wrapping operation of each feeder and to release each warp-thread after it has been wrapped round its needle and immediately prior to a loop-drawing operation of the associated needle, for the purpose described.

EDWIN WILDT.
